UNITED STATES PATENT OFFICE.

OSCAR W. JOHNSON AND ROBERT MILNE, OF ROCKFORD, ILLINOIS, ASSIGNEES TO
WARD PUMP COMPANY, OF ROCKFORD, ILLINOIS, A CORPORATION OF ILLINOIS.

SPRAYER.

1,345,598.

Specification of Letters Patent.

Patented July 6, 1920.

Application filed January 29, 1918. Serial No. 214,337.

To all whom it may concern:

Be it known that we, OSCAR W. JOHNSON and ROBERT MILNE, citizens of the United States, residing at Rockford, in the county of Winnebago and State of Illinois, have invented certain new and useful Improvements in Sprayers, of which the following is a specification.

This invention relates in general to apparatus for spraying trees, shrubbery and the like for immunizing and freeing them of insect growth, and has more particular reference to the construction of the spray nozzle and the means for controlling the delivery of the spraying fluid therefrom.

In the use of such apparatus it is desirable to obtain a variable spray so that far and near objects may be sprayed with a proper delivery by simply manipulating at will a control member to change the spray from a widely scattering character for close work to a narrow stream-like spray for objects more distant. It is also desired to obtain a graduated change in the character of the spray from one limit to the other according to the position and nature of the objectives; so that the work may be performed in a most effectual and economical manner. Also, in some instances it is necessary for the operator to climb into trees in order to reach high branches; consequently, taking into consideration the various and changing requirements of the work, it is desired to deliver instantly the proper spray to the objectives within the range of the operator.

In the present invention, we have aimed to provide a spray nozzle and control therefor of generally improved construction, whereby the desired objects mentioned above may be attained in a most practical and satisfactory manner.

In furtherance of this general object, we have incorporated in our spraying device various novel features which will be briefly mentioned at present and more fully described in the following specification. One of the features resides in the provision of means for mixing the fluid in a novel manner to produce the different spraying effects. Another resides in the special manner in which the liquid is delivered to the mixing means, and another in the manually operable adjusting means for governing the delivery of liquid to the mixer and conse-

quently determining the nature of the spray delivered therefrom. By reason of the foregoing, the high pressure of the liquid is handled in such a way as to prevent vibration and sharp jerking of the spraying tool when commencing to spray, and a manually adjustable control member is provided by means of which the operator by simple finger manipulation may conveniently and instantly commence to spray and secure any variation in the character of the discharge. In fact, the spraying tool is practically a one-hand tool, that is, it can be carried and manipulated entirely by either hand, and as a result, various advantages follow. An operator may easily work while in a tree, employing one hand to carry and manipulate the spraying tool and the other to hold himself in position. Furthermore, the tool is so designed that the attaching hose connects directly to the rear end of the tool, or rather, to the handle portion thereof in direct alinement with the delivery nozzle so that the hose will not become quickly worn and leaky from handling.

These and other objects and advantages will be more readily appreciated as the invention becomes better understood by reference to the following description when considered in connection with the accompanying drawings, in which—

Figure 1 is a side elevation of a sprayer embodying our improvements;

Fig. 2, a longitudinal sectional view through the sprayer;

Figs. 3, 4, 5 and 6, views respectively illustrating the several variations in the character of the spray delivered by our improved sprayer;

Fig. 7, a longitudinal sectional view through the nozzle of the sprayer and illustrating a full working size of the present embodiment of our improvements; and

Fig. 8, a cross-sectional view through the nozzle taken on the line 8—8 of Fig. 7.

Referring especially to Figs. 2, 7 and 8 illustrating the construction of the nozzle, it will be observed that the latter consists primarily of a suitably shaped casing designated generally by reference character 11 threadingly engaged on the end of a pipe section 12 through which the spraying fluid is delivered under a high pressure to the casing. The fluid is adapted to pass through certain passages within the casing

to a chamber 13, from whence it is delivered through a small orifice 14 in a disk 15, which defines the outer wall of said chamber. A centrally apertured cap 16 threadedly engaged on the casing 11, as shown, 5 clamps the disk 15 and a rubber spacing gasket 17 to the casing 11. Thus, a sealed circular chamber is provided at the end of the casing 11 having a small central dis- 10 charge orifice 14. Within the casing 11, we have provided a valve adapted to be normally held seated or closed partly by the high pressure of the liquid for preventing the same from entering the chamber 13. Referring especially to Fig. 7, it will 15 be seen that the movable element 18 secured to an operating rod 19 is adapted to be seated on the valve seat ring 21 which has a central passage 22. This valve seat mem- 20 ber, clamped in position by the pipe 12 against an annular shoulder 23 integral with the casing may be removed and reversed after the casing 11 is unscrewed from the pipe section 12. In order to insure a tight 25 valve, the element 18 is provided with a face 24 of rubber or other suitable material adapted to seat on the member 21. While the means for operating the valve rod 19 will be described hereinafter, it might be 30 here mentioned that the rod is constantly urged by an expansion spring 25 in a length- 35 wise direction for holding the valve 18 closed. Thus, in the intervals between spraying the liquid supply is shut off by the valve 18 which is held seated, not only by the spring 25 but also by the high pressure of the liquid.

Intermediate the valve 18 and the chamber 13 we have provided means for causing liquid to be delivered to the chamber so 40 that it will revolve within the same and be discharged through the orifice 14 in a centrifugal spray and also for causing the delivery to the chamber to be varied in a 45 predetermined manner by novel means for modifying the character of the spray. Generally stated, this means comprises a series of spirally inclined passages through which the liquid having passed through the valve 50 opening 22 will be delivered to the chamber 13 at circumferentially spaced points so as to revolve or swirl rapidly within the chamber and discharge through its central orifice 14 in a relatively wide delivering centrif- 55 60 65 70 75 80 85 90 95 of which are of a centrifugal character so that even in the narrow stream the delivery is broken up and diffused instead of being in a substantially solid body. These distinct variations, however, may be more or less graduated by only partially opening or closing the several ports 32, 33 and 34.

Means for manually operating the valve control rod 19 will now be described. To the end of the pipe 12 opposite the nozzle is threadingly secured a casing 35 having a slightly offset fuel passage 36 to which a supply hose is adapted to be attached. The end of the rod 19 adapted to be operated extends through a stuffing box 37 and is threadingly secured to a cylindrical member 38 slidable lengthwise in the casing and provided with a rack face 39. A companion rack 41 meshes with the rack 39 and is formed integral with a hand lever 42 interposed between and pivotally mounted upon the spaced ears 43 projecting laterally from the casing 35. This hand lever 42 is arranged so that it may be manipulated by the same hand that carries the spraying device, and by reference to Fig. 1 it will be evident that in view of the fact that the manipulation is a simple hand closing movement the lever operating movement is quite limited. However, as will be presently seen, we obtain from this limited lever movement the desired movement of the valve 19 for securing the various spray deliveries. In addition to this, we transmit to the valve operating rod 19, the movement imparted to the lever 42 in a particularly advantageous manner, by which the valve 18 will be unseated against the high liquid pressure by a powerful leverage, so that this first valve may be opened very evenly without vibration or jerking of the valve, and by which the valve rod is subsequently moved with less leverage advantage but faster with respect to the lever movement for opening the series of ports which modify the spraying effect. Various means may be interposed between the lever 42 or a similar operating member and the valve 19 for obtaining the desired valve movement, and in the present instance we have illustrated a single embodiment employing co-operating rack elements, the driving element of which is formed integral with the operating lever, which in turn is pivotal about different centers to change the leverage for the purpose just previously mentioned. Referring to Figs. 1 and 2, it will be noted that the lever is of a general bell crank shape provided with a pivot pin 44 projecting laterally from both sides of the lever at the juncture of its arms, and a similar pivot pin 45 positioned adjacent to the outer end of the rack arm of the lever. That portion of the rack 41 engaging the rack 39, as shown in Fig. 2, is formed on an arc struck from the center of the pivot

45, and the remaining portion is formed concentric with the pivot 44. Normally, the lever 42 is disposed in the position shown, with the opposite ends of the pin 45 engaging the ends 46 of recesses formed in the 70 sides of the casing 35 and the ends of the pivot pin 45 disposed in the ends 47 of arcuate slots 48 formed in the ears 43 concentric with the pivot pin 45 when the same is in the position shown. By reason of this construction, when the lever 42 is initially moved in a counter-clockwise direction, viewing Fig. 2, it will swing about the pivot 45 and unseat the valve 18 with a very powerful leverage action by reason of the position of the pivot 80 pin 45, and upon further movement of the lever for the purpose of opening the ports 32, 33 and 34, the lever will swing about the pivot pin 44 which has, by the initial operating movement of the lever, been moved into 85 contact with the ends 49 of the slots 48. By this means the valve 18 may be easily opened either gradually or instantly by a simple hand closing movement against a very high liquid pressure, thus obviating entirely the 90 difficulties following from previous spraying tools wherein the adjustment was very slow or was subject to vibration and kicking due to the impractical manner in which the valve was opened against the high fluid 95 pressure. In Fig. 2, we have indicated the positions assumed by the lever for producing the several spraying effects illustrated in Figs. 3, 4, 5 and 6, these positions being substantially indicated by the dotted lines 3', 4', 100 5' and 6' respectively. It will, of course, be understood that the operation is not necessarily limited to these particular variations, since as mentioned above, the changes may be made gradually by slowly adjusting the 105 operating member intermediate the points indicated. The operator can, however, distinctly feel the change from the wide spray 3' to the more narrow spray 4', this being due to the fact that the change in leverage 110 occurs practically at the time the port 32 is opened. This is very desirable as it enables the operator to govern the spray largely by feeling the position of the lever 42 rather than by continually watching the delivery 115 of the liquid.

From the foregoing it will be manifest that the spraying device is practically a one hand tool, that is, it can be carried and operated entirely by one hand. This is due 120 mainly to the construction and arrangement of the valve operating means, by reason of which the various spraying effects are obtained as described above, by a simple hand closing movement. This adjusting means is 125 particularly advantageous because of the fact that the valve 18 may be easily, and either gradually or instantly, unseated against a high liquid pressure. Our improvements provide for securing these vari- 130

ous valve movements by simple operation of a hand lever in which the leverage is changed automatically while operating the lever to obtain the desired movements. In conclusion, another important advantage of our improvements might be mentioned. The spraying liquid contains particles which under the most favorable conditions clog the nozzle in a very short time so that the same must be quite frequently disassembled and cleaned. In other constructions it is almost invariably necessary to stop the pumping means supplying the liquid in order to clean the nozzle, but with our improvements the parts of the nozzle may be quickly disassembled and cleaned at any time during the operation. This is because the valve 18 normally stops the delivery and permits of removing the cap 16 and the member 26 for cleaning the latter and the nozzle parts without stopping the operation of the pump. It is believed that the foregoing description conveys a clear understanding of the construction and operation of our improvements and of the objects prefaced above, and it should be understood that while we have illustrated one working embodiment of our improvements, various changes might be made in the construction and arrangement without departing from the spirit and scope of the invention as expressed in the appended claims.

We claim:—

1. In a spraying device, the combination of a mixing chamber, a conduit for supplying liquid thereto, a valve in the conduit, means for causing the liquid to revolve in the chamber so as to be delivered therefrom in a relatively wide spray, valve controlled means for delivering liquid to the chamber separate from said continuous delivery thereto for varying the character of the discharge from the chamber, and means controlled from a common operating member having a double fulcrum for opening the first mentioned valve with a given leverage advantage whereby liquid will be delivered rotatably to the chamber and for subsequently operating said valve controlled means with less leverage advantage but greater movement to vary the character of the discharge.
2. In a device of the character described,

a delivery nozzle, a valve controlled passage through which liquid is supplied to said nozzle including a valve normally held seated by pressure of liquid in the passage and another valve for modifying the character of the discharge from the nozzle, and a common operating means for operating both valves having a double fulcrum and constructed to unseat the first valve against said pressure with a greater leverage advantage than when operating the second valve.

3. In a spray gun device of the character described, the combination of a delivery nozzle containing valve means for varying the character of the discharge, a bell crank member for actuating the valve means one arm of which bell crank is manually operable and the other connects with said valve means, and a double fulcrum for said bell crank member for changing the leverage during operation of said member.

4. In a spray gun device of the character described, the combination of a delivery nozzle containing valve means for varying the character of the discharge, a segmental rack for actuating the valve means and having a changeable fulcrum, and means for oscillating the rack whereby the fulcrum will be changed during such oscillation to secure the greatest leverage advantage during the initial movement and less leverage but greater valve movement during subsequent oscillation of the segmental rack.

5. In a spray gun, the combination of a nozzle having a chamber in which the liquid rotates and from which it is delivered in a relatively wide spray, a series of ports communicating with said chamber, a valve for opening said ports in succession, a valve for controlling the supply of liquid to said chamber and said ports, a manually operable lever, and means operable between said lever and said valve means and having a double fulcrum so arranged as to cause said supply valve to be opened during initial movement of the lever with a given leverage advantage and said port opening valve means to be actuated upon subsequent movement of said lever with less leverage advantage but greater movement.

OSCAR W. JOHNSON.
